CLAIM

The ornamental design for a shelf to be attached to pegboards or the like, as shown and described.

DESCRIPTION

FIG. 1 is a front and top perspective view of the shelf to be attached to pegboards or the like showing our design;

FIG. 2 is a top plan view thereof;

FIG. 3 is a bottom plan view thereof;

FIG. 4 is a front elevational view thereof;

FIG. 5 is a back elevational view thereof; and

FIG. 6 is a side elevational view thereof, showing the right hand side, as viewed in FIG. 1.

*FIG. 1**FIG. 6**FIG. 2**FIG. 3**FIG. 4**FIG. 5*
